(57) **CLAIM**

The ornamental design for a mounting assembly for a support rail attachment as shown and described.

DESCRIPTION

FIG. 1 is a top, front, right perspective view of a mounting assembly for a support rail attachment showing my new design;

FIG. 2 is a bottom, rear, left perspective view thereof;

FIG. 3 is a bottom view thereof;

FIG. 4 is a top view thereof;

FIG. 5 is a rear view thereof;

FIG. 6 is a front view thereof;

FIG. 7 is a left side view thereof;

FIG. 8 is a right side view thereof;

FIG. 9 is a top, front, right perspective view thereof, shown with example environment in a first mounting configuration;

FIG. 10 is a top, front, right perspective view thereof, shown with example environment in a second mounting configuration; and,

FIG. 11 is a top, front, right perspective view thereof, shown with example environment in a third mounting configuration.

The uneven-length broken lines immediately adjacent to the shaded area define the bounds of the claimed design and form no part thereof. The even-length broken lines depicting the remainder of the article form no part of the claimed design. The example environment shown in broken lines in FIGS. 9-11 forms no part of the claimed design. The uneven-length broken lines surrounding the article in FIGS. 9-11 represent boundaries of the example environment depicted, and form no part of the claimed design.

The article is shown in FIG. 11 with a symbolic break in its length, and the appearance of any portion of the article between the break lines forms no part of the claimed design. The claim is directed to the collective appearance of the mounting assembly for a support rail attachment shown in the figures. The components of the claimed design are arranged on the drawing sheets for the convenience of illustration, and the relative positioning of the components

(Continued)

of the mounting assembly for a support rail attachment forms no part of the claimed design.

1 Claim, 8 Drawing Sheets
